(57) **CLAIM**

The ornamental design for knee parts for prostheses, as shown and described.

DESCRIPTION

FIG. 1 is a first perspective view of knee parts for prostheses in accordance with aspects of the present disclosure. FIG. 2 is a rear view of the knee parts for prostheses in accordance with aspects of the present disclosure. FIG. 3 is a top view of the knee parts for prostheses in accordance with aspects of the present disclosure. FIG. 4 is a bottom side view of the knee parts for prostheses in accordance with aspects of the present disclosure. FIG. 5 is a front view of the knee parts for prostheses in accordance with aspects of the present disclosure. FIG. 6 is a first side view of the knee parts for prostheses in accordance with aspects of the present disclosure. FIG. 7 is a second side view of the knee parts for prostheses in accordance with aspects of the present disclosure. FIG. 8 is a second perspective view of the knee parts for prostheses in accordance with aspects of the present disclosure. FIG. 9 is a first perspective view of knee parts for prostheses in accordance with additional aspects of the present disclosure. FIG. 10 is a second perspective view of the knee parts for prostheses in accordance with additional aspects of the present disclosure. FIG. 11 is a rear view of the knee parts for prostheses in accordance with additional aspects of the present disclosure. FIG. 12 is a first side view of the knee parts for prostheses in accordance additional with aspects of the present disclosure. FIG. 13 is a top view of the knee parts for prostheses in accordance with additional aspects of the present disclosure. FIG. 14 is a bottom view of the knee parts for prostheses in accordance with additional aspects of the present disclosure. FIG. 15 is a front view of the knee parts for prostheses in accordance with additional aspects of the present disclosure; and, FIG. 16 is a second side view of the knee parts for prostheses in additional accordance with aspects of the present disclosure. Any surfaces of the design not shown, including interior surfaces, form no part of the claimed invention. The broken lines subject matter shown in the drawings forms no part of the claimed design.
